WELL STRAINER

Filed Jan. 25, 1930

FIG 1.

FIG 3.

FIG 4.

FIG 5.

FIG 5.

Inventor

J. M. LOSACK

UNITED STATES PATENT OFFICE

JOHN M. LOSACK, OF ORCHARD, TEXAS

WELL STRAINER

Application filed January 25, 1930. Serial No. 423,427.

This invention relates to well strainers and particularly to certain improvements in the well strainer shown in my Patent No. 1,634,547 granted July 5, 1927.

5 The general object of the present invention is to cheapen the cost of construction of the well strainer shown in my prior patent without, however, affecting in any way the effectiveness of the well strainer and a further object is to provide a well strainer of 10 this character wherein the tubular body or pipe forming the body of the strainer need not be very deeply grooved or in some instances need not be grooved at all, thus preventing the pipe from being unduly weakened and, therefore, rendering it liable to break when the strainer is driven into the ground.

20 A further object is to provide a construction of this character wherein the fluid entering the strainer is subjected to a plurality of straining operations.

Other objects will appear in the course of the following description.

25 My invention is illustrated in the accompanying drawings, wherein:—

Figure 1 is a fragmentary elevation of a well strainer constructed in accordance with my invention;

30 Figure 2 is a fragmentary elevation of a slightly modified form of strainer;

Figure 3 is an enlarged vertical sectional view of one wall of the pipe and the strip applied thereto constructed in accordance with one form of my invention;

35 Figure 4 is a section on the line 4—4 of Figure 3;

Figure 5 is a vertical section like Figure 3, but showing another embodiment of my invention;

40 Figure 6 is a like view to Figures 5 and 3 but showing still another embodiment of my invention.

45 Referring to Figure 1, the strainer element consists generally of a tubular body 10, as for instance, a length of pipe which may be provided at its lower end with a pointed element whereby it may be driven into the ground as illustrated in my prior patent, this pipe being preferably grooved as

55 at 11 to receive a metallic strip or tape designated 12, this tape being provided with a plurality of transverse slots 13. As illustrated in Figure 3, the wall of the pipe 10 is formed with a groove 14 which is disposed 60 immediately beneath the ribbon or strip 12, this groove being connected to the interior of the pipe by a plurality of relatively small perforations 15. In Figure 1, the metallic ribbon 12, is illustrated as extending spirally around the pipe and the groove 11 is spirally cut around the pipe, but I do not wish to be limited to this as the groove 11 might be extended circumferentially around the pipe or extend longitudinally of the pipe, 65 such a longitudinal groove being shown in Figure 2. In this case, of course, the ribbon 12 will extend longitudinally. The recess 11 within which the ribbon is disposed may have one groove 14 formed in it, as shown in 70 Figure 3 or as illustrated in Figure 5 may be formed with a plurality of grooves 14 or 14^a and while preferably these grooves 14 or 14^a are formed in the pipe 10 itself, I do not wish to be limited to this as it is entirely 75 possible to form the grooves, as for instance the grooves 16, as shown in Figure 6 in the ribbon.

There may be one or more of these grooves in the ribbon or metallic strip 12. In either 80 case, there is formed a duct extending circumferentially around the pipe or spirally around the pipe or longitudinally along the pipe and water will enter through the slits 13 in the ribbon and pass around the pipe and 85 enter the interior of the pipe through the perforations 15.

It will be understood that I do not wish to 90 be limited to the use of the ribbon arranged in a spiral around the pipe or disposed in a special groove 11, though this I regard as the preferable way of forming the strainer. It will be seen that with this construction, the ribbon is held between the walls of the recess 11 so that when the pipe is driven, the 95 ribbon cannot get out of position. It will further be seen that by this construction, a clogging of any one of the slits 13 or a clogging of the grooves 14 or 14^a at any particular point will not vitally affect the strainer 100

nor the clogging of any of the perforations 15, as if one or more of the perforations 15 are clogged, the water will simply flow along the duct formed by the grooves 14 or 14^a until it finds a perforation which is clear.

5 At the same time the water is submitted to two straining actions in passing through the slots 13 and through the perforations 15. The metallic ribbon or strip 12 may be disposed in the recess 11 either loosely, the ends 10 of the strip being held as by welding or soldering or the strip might be soldered or welded along its entire length. Preferably, it will be loosely disposed so that water may enter around the edges 11 as well as through 15 the slots 13.

While I have illustrated the groove 14 as being disposed on the middle line of the strip 12, it is obvious that it might be disposed in other positions with relation to the strip 20 and yet accomplish the desired result.

I claim:—

1. A well strainer comprising a tubular body having a spiral recess extending along the body along its outer surface, the bottom 25 of the recess being formed with a groove and there being perforations extending from the bottom of the groove into the interior of the body and a metallic ribbon-like strip disposed in said recess, the strip being transversely slotted throughout its length.

2. In a well strainer, a tubular body having a recess formed therein, a metallic strip disposed in the recess, the strip and the body 35 having confronting faces, one of said faces being formed with a groove extending longitudinally of the strip, the body having perforations opening into said groove and the strip being formed with slits transverse to the strip and opening into said groove.

40 In testimony whereof I hereunto affix my signature.

JOHN M. LOSACK.
